UNITED STATES PATENT OFFICE.

RUDOLF BERG, OF PITTSBURG, PENNSYLVANIA, ASSIGNOR OF ONE-HALF
TO FERDINAND WENIG, OF SAME PLACE.

BLOWER.

SPECIFICATION forming part of Letters Patent No. 674,832, dated May 21, 1901.

Application filed January 7, 1901. Serial No. 42,378. (No model.)

To all whom it may concern:

Be it known that I, RUDOLF BERG, a citizen of the United States, residing in Pittsburg, in the county of Allegheny, in the State of Pennsylvania, have invented certain new and useful Improvements in Blowers, of which the following is a specification.

This invention has reference to an improved blower for supplying large quantities of air under pressure for use in the arts, said blower being constructed either with a single or with a plurality of easily-running air-forcing wheels in such manner that when their action is reversed the apparatus can be used as a circulating-pump for lifting or mixing liquids; and the invention consists of an air-blower which comprises an exterior stationary casing, heads for the same provided with air-inlet openings, an interior air-forcing wheel composed of a web, and a circumferential flange having slots inclined at a suitable angle to the axis of the wheel and arranged at one or both sides of the web.

The invention consists, further, of a blower having a plurality of air-forcing wheels; and the invention consists, lastly, in the construction of the air-forcing wheel itself and in certain other details of construction, which will be fully described hereinafter and finally claimed.

In the accompanying drawings, Figure 1 represents a vertical longitudinal section of my improved air-blower on line 1 1, Fig. 2. Fig. 2 is a vertical transverse section on line 2 2, Fig. 1. Fig. 3 is a vertical longitudinal section of my improved blower arranged with a plurality of air-forcing wheels; and Figs. 4 and 5 are respectively a vertical transverse section on line 4 4, Fig. 5, and a similar longitudinal section on line 5 5, Fig. 4, of a circulating-pump having the same construction of air-forcing wheel as the blower.

Similar letters of reference indicate corresponding parts.

Referring to the drawings, A represents the air-forcing wheel of my improved air-blower. This air-forcing wheel is made of a cylindrical flange and a central web C, which is placed by a suitable hub a on the shaft I. The circumferential flange of the air-forcing wheel A is provided with a number of inclined slots B, which are preferably arranged at each side of the web C, the slots B having

an inclination with respect to the axis of the wheel preferably tangential to an interior circle which is drawn concentrically with the hub of the air-forcing wheel A, as shown in dotted lines in Figs. 1 and 4. The inclined air-forcing slots are arranged equidistantly from each other and of equal width and length. The air-forcing wheel A is surrounded by an exterior casing D, which is closed at the sides by heads F, that are provided with central bearings G for the shaft I, said bearings being concentrically adjusted by means of screws H, so as to properly center the shaft. The heads F are provided with air-inlet openings f, which are adjacent to the center bearings G and which communicate with the spaces E, that are formed in the interior of the casing between the web C and the heads F of the same. The central bearings G are provided with suitable lubricating devices, so that the easy running of the rotating air-forcing wheel is obtained. One end of the shaft is provided with a longitudinal keyway for being coupled with the shaft of a dynamo-electric machine or other motor, as shown in Figs. 2, 3, and 5. The circumference of the air-forcing wheel A sidewise of the slotted portion of the same is fitted closely to the inwardly-projecting flanges d of the casing D, as shown clearly in Fig. 2. The air-forcing wheel is arranged either concentrically with the casing or slightly eccentrically thereto, as shown in Fig. 1, in which latter case it is placed nearer to the portion of the casing adjacent to the outlet-opening, so that the air taken in by the wheel is gradually compressed and forced toward and through the outlet-opening. The inclined slots arranged in the circumference of the air-forcing wheel cut through the air and force the same in wedge-shaped portions through the slots, owing to the rapid rotation of the wheel, so that the air is drawn in from the spaces E and transmitted into the annular space formed by the exterior casing D around the circumference of the wheel A. By the rotation of the air-forcing wheel the employment of centrifugal power is entirely dispensed with and a blower obtained which permits the supplying of large quantities of air without exerting any great friction on the air particles, which is objectionable.

The blower may be constructed as a mul-

iple or compound blower by enlarging the exterior casing D and arranging two or more air-forcing wheels A' A² A³ within the casing, as shown in Fig. 3. The sides of the casing 5 D are closed by heads F, similar to those used in the single-acting blower. (Shown in Fig. 2.) It is preferable to use an uneven number of blowers, three being shown, the intermediate one, A³, being provided with inclined 10 slots B³ at both sides of its web, while the outer air-forcing wheels A' A² are provided with inclined slots B' B³ at the outer portion of the webs, which slots are, however, equal in size to the inclined slots at both sides of 15 the web of the intermediate air-forcing wheel. In this case the air passes through the openings f in the heads F into the spaces E' and E⁴ of the outer air-forcing wheels A' A² and then through the inclined slots in the outer 20 circumference of the said wheels into the spaces E³ between the outer and intermediate wheels, the casing being provided with annular spaces E² and E⁵ and an intermediate annular space E⁶, that extend around the 25 outer wheels A' A² and the intermediate or central wheel A³. The air is forced from the spaces E³ through the inclined slots B³ of the center wheel into the annular chamber E⁶ and from the same through the outlet-opening 30 L to the conducting-pipe connected with the place of use, as shown by the arrows in Fig. 3.

A compound blower having three wheels may be called a "double" compound blower, 35 while a blower having four or five wheels can be termed a "triple" compound blower, and one with six or seven wheels a "quadruple" blower, &c. In all cases, however, the hub of the air-forcing wheels has to be secured to 40 the shaft I by means of nuts and jam-nuts M, as shown in Figs. 2 and 3. By the compound blowers a higher pressure can be obtained, while the easy running of the same with considerable less power is obtained than 45 with the centrifugal or other blowers heretofore in use. The wheel A can also be used for a circulating-pump, in which the action is reversed—i. e., in place of forcing air a suitable liquid is raised or mixed with another 50 liquid. Such a circulating-pump is shown in Figs. 4 and 5, in which the location of the slotted forcing-wheel produces the raising of the liquid through the stand-pipe N into a semi-circular chamber E^X at the upper part of the 55 casing and then through the chamber E^X and through the inclined slots of the rotary wheel A to the annular channel E of the same to the outlet-pipe L. A drain-pipe P and cock Q are arranged at the lower part of the exterior casing D for properly draining the casing D when the connection with the outlet-pipe is interrupted. The heads F are in this 60 case also provided with hub-shaped bearings G, as shown in Fig. 5. The air-forcing wheel 65 is of exactly the same construction as in the air-blower, the inclination of the slots in the

circumference of the same being indicated in dotted lines, and arranged tangential to a circle drawn concentric with the forcing-wheel at the inside of the same, as shown in Fig. 4. 70 The suction or inlet stand-pipe N can be connected with different supply-pipes whenever the lifting and mixing of different liquids is required.

Having thus described my invention, I 75 claim as new and desire to secure by Letters Patent—

1. An air-blower, consisting of an exterior annular casing provided with an outlet-opening, heads at the opposite sides of the casing 80 provided with inlet-openings, and an interior rotary air-forcing wheel provided with a central web, and a circumferential flange having slots at both sides of said web, said slots having a suitable inclination to the axis of the 85 wheel, substantially as set forth.

2. In an air-blower, consisting of an exterior casing, provided with inwardly-projecting flanges and an outlet-opening, heads attached to opposite sides of said casing and provided 90 with inlet-openings, and an interior rotary air-forcing wheel provided with a web and a circumferential flange adjacent to the flanges of the casing and with slots having an inclination to the axis of the wheel, and central 95 bearings in the heads for supporting the shaft of the air-forcing wheel, substantially as set forth.

3. An air-blower, consisting of an exterior casing having an outlet-opening and a plurality of interior annular channels, heads applied to opposite sides of said casing, and provided with inlet-openings, and a plurality of air-forcing wheels provided each with a circumferential flange having slots arranged at a 105 suitable inclination to the axis of said wheels, substantially as set forth.

4. An air-blower, consisting of an exterior casing provided with an outlet-opening and a plurality of annular channels in the same, 110 heads attached to opposite sides of said casing and provided with inlet-openings, a shaft supported in central bearings of the heads, and a plurality of air-forcing wheels on said shaft, the intermediate air-forcing wheel being provided with slots at both sides of its web, while the outer air-forcing wheels are provided with slots at the outer sides of the webs adjacent to the heads, substantially as 115 set forth.

5. In a blower, pump or similar structure, an air-forcing wheel of circular shape, provided with a web and a circumferential flange having slots arranged at a suitable inclination to the axis, substantially as set forth. 125

In testimony that I claim the foregoing as my invention I have signed my name in presence of two subscribing witnesses.

RUDOLF BERG.
